LEVELING ROD

Filed Aug. 29, 1927

UNITED STATES PATENT OFFICE

ADOLPH LANGSNER, OF CHICAGO, ILLINOIS, ASSIGNOR TO EUGENE DIETZGEN COMPANY, OF CHICAGO, ILLINOIS, A CORPORATION OF DELAWARE

LEVELING ROD

Application filed August 29, 1927. Serial No. 216,306.

My invention relates to leveling rods used by surveyors and others, and especially to an extension leveling rod composed of two sections whereby the rod may be extended in length and may be held in such position of adjustment. Rods of this type are provided with a lower section designed to rest upon the ground or other support and provided with scale markings on its front. An upper section is assembled to this lower section to slide thereon and this upper section carries a target vertically adjustable thereon. Heretofore the extension leveling rods have been provided with clamps for holding the upper slidable section in its extreme extended position of adjustment with respect to the lower section. An improved type of such a clamping means is shown in my co-pending application, Serial No. 174,278, filed March 10, 1927.

Experience has shown, however, that these prior clamping devices have been ineffective positively to hold the upper section in such extreme adjustable position with respect to the lower section, and considerable annoyance and loss of time has been occasioned by the necessity of readjusting the upper slidable section with respect to the lower section due to the fact that when the operator of the leveling rod moved to a new location to take an additional measurement and when he placed the leveling rod on the ground, in the very act of placing he generally dropped the lower section into contact with the ground when so placing it. This impact of the lower section with the ground caused the upper section to shift slightly downwardly in spite of the clamping device, so that the accurate setting of the upper section was disturbed in spite of the clamping device.

One of the objects of my present invention is to provide a positive locking means for interlocking the two sections so that they are incapable of shifting relatively even when the bottom section is impacted against the ground. In the present disclosure this locking means is preferably an automatic locking means adapted to come into operation when the upper section is slid outward-

ly or upwardly to its extreme extended position.

Another object of my invention is to provide an automatic locking means between the upper and lower sections of the leveling rod which is operable by the movement of one of said sections relatively to the other.

Another object of my invention resides in providing an improvement in the construction disclosed and claimed in my prior mentioned application by forming the spring which therein functions to prevent the nose of the locking screw from indenting the wood of one of the sections and for also increasing the area available for clamping engagement of the rod section, so that such spring in addition provides the automatic means for locking the sections in extreme extended position of adjustment. In this improved construction the clamping device of my former construction co-operates with the automatic lock to prevent side play or rattling of the sections.

These and other objects of my invention will be apparent from a perusal of the following specification when taken in connection with the accompanying drawings wherein—

Figure 1 shows a view of the leveling rod with the upper extension lowered;

Fig. 2 shows a view with the upper section in the raised position and with the pin of the automatic stop seated in the apertured boss of the locking spring;

Fig. 3 is an enlarged sectional view of one form of my automatic stop, the same being that form wherein my automatic stop is combined with the clamping mechanism shown in my before mentioned application;

Fig. 4 is a front view thereof; and

Fig. 5 is a detailed perspective view of the combined spring for the clamp and having an extension to provide the automatic stop.

Referring now to the drawings, the rod is formed in two sections 10 and 12 in a manner common to extension leveling rods. The upper section 12 is adapted to carry a target at its upper end. This target is not shown in the drawing. This upper section

may be termed the movable section. The lower section is designed to rest upon the ground or any other support. Ordinarily the front of the stationary scale 10 has the 5 usual scale markings.

As shown in the drawings, the two sections are adapted to be held in slidable assembled relation by means of a clip 13 preferably fastened to one face of the bottom 10 portion of the section 12. This clip is of the usual U-shaped formation and is provided with the usual aperture through which the indicating marks of the front face on the lower section may be viewed. In addition 15 the lower end of the section 10 is provided with a stop or abutment against which the bottom end of section 12 rests when the upper and lower sections are slid into compact position as shown in Fig. 1.

20 In the practical operation of an extension leveling rod when it is desired to take measurements of increased height, the movable section 12 is slid upwardly to its extreme position of adjustment and the target may 25 then be slid vertically to the desired adjustment as is well known.

My present invention comprehends means for immovably and rigidly locking the upper section in its extreme extended position 30 with respect to the lower section, and I preferably form this means so that the sections will be so locked automatically by the sliding movement of the upper section relative to the lower section.

35 This automatic locking means is also constructed and arranged to be instantly released so as to permit the upper section to be freely shifted down or below such predetermined adjustment. Obviously this

40 automatic lock may take many variant forms. In the present instance I have provided a simple type of automatic locking means constructed of a leaf spring attached to one of the sections, preferably the lower,

45 and a pin or a lug projecting from the side of the other section. The spring is formed with a laterally bent free end and with an aperture adjacent the free end, and this spring is arranged to overlie the path of

50 movement of the projecting lug carried by the upper section so that when the upper section is moved relatively to the lower section the lug will ride under the free end of the spring, will slightly lift the spring so that the lug will enter the hole or aperture in the spring and will automatically lock therein. By lifting the free end of the

55 spring the lock is free to ride out of its locking aperture so that the two sections 60 may be shifted again one relatively to the other.

While this particular spring construction of automatic lock may take many forms of construction, I prefer to adopt this particular spring form of automatic lock and to

combine it with the clamping mechanism disclosed and claimed in my prior application heretofore mentioned. In this manner the spring of my automatic lock will form an extension of the spring used in my clamping construction so that such spring will have a dual function: first, its function as a means for preventing the end of the clamping screw from biting or indenting the wood of one of the sections and for providing a greater superficial area of clamping contact; and second, the lower end of the spring or the spring extension will form the leaf spring portion of the automatic lock as just herein described for co-operating with the projecting lug on the other section of the leveling rod.

For the purpose of describing the manner of co-operation of my present type of automatic interlocking spring with the clamping device of my prior application, it will be necessary for me to briefly describe the construction and operation of such clamp. It will be understood, however, that the details of construction of the clamp itself are 30 not claimed herein, but are made in my prior mentioned application, the claims of the present application being confined to such parts of the clamp as co-operate and combine with my spring automatic interlock 35 herein shown and described.

Referring now particularly to the clamp, it comprises a substantially rectangular hollow sleeve 16 suitably fastened to the lower section 10. A yoke 18 has two feet 20 which are riveted to the front wall of the sleeve 16 so that the yoke is held in position upon the sleeve. The front wall of the sleeve 16 is provided with an aperture through which the nose 22 of a clamping screw 24 is adapted to project. The outer end of the clamping screw threadedly engages the threaded aperture 26 of the yoke 18. Intermediate its ends the clamping screw 24 is provided with a turning wheel 28.

In the present form of my invention I prefer to construct the spring portion of my automatic interlock as shown in perspective of Fig. 5 of the drawings, wherein the upper portion 30 of this spring is slightly bowed, 115 being provided on its upper edge with a lateral extension 32 and at the lower termination of the bowed portion 30 with a shoulder 34. The lower portion 36 of the spring extends in a substantially uniform plane 120 toward its lower end where it is provided with an outstanding boss 38 apertured as at 40, and the extreme lower tip 42 of the extension is turned upwardly. This spring is made of any resilient material. It is installed in position as shown clearly in Fig. 3 of the drawings in such a manner that the bowed portion 30 is placed between the front wall of the lower section 10 and the nose 22 of the threaded screw. The upper 125

lateral extension 32 of the bowed portion extends over the upper edge of the sleeve 16 and the lower shoulder 34 of the bowed portion is positioned under and in contact with 5 the lower portion of the sleeve 16. By preference, the extension 32 and also the shoulder 34 are sprung a trifle so that they will converge slightly and will grip the lower edges of the side wall of the sleeve. Thus the 10 spring is held somewhat after the manner of a clip with the result that the spring will retain itself in position within the sleeve even though the rod section is not present. As the spring is resilient it can of course 15 be readily pulled off and is positioned by merely pressing it into place. This construction forms a simple and effective means for keeping the spring in the frame and simplifies the act of assembly.

20 It will be noticed that the sleeve 16 is located on one face of the lower section 10 in such a manner that the depending portion 36 of the spring 30 overlies the path of movement of the upper section as it slides 25 vertically with respect to the lower section. This upper section carries on its adjacent face an outwardly projecting lug 44. This lug as the section 12 slides upward is directly in the path of the hole 40 in the spring 30 extension 36 so that when the section 12 reaches its extreme upper position toward the end of this upward movement, lug 44 will ride under the upwardly bent nose 42 of the spring and will raise the spring so 35 that the projection 44 will snap into the hole 40 and thus lock the upper section 12 in predetermined extreme, extended position. This lock is thus automatic in its operation by the sliding of the two sections 40 relatively. At the same time it will be observed that by lifting the free end 32 of the extension 36 the interlock is instantly released so that the section 12 may be slid upwardly again in position as shown in 45 Fig. 1.

It will be appreciated that my improved locking device is of simple construction, is sure and automatic in its operation and may be instantly released to permit a shifting of 50 the relatively slidable sections. It will be further appreciated that my present form of automatic interlock, that is the spring type of automatic interlock for the leveling rod sections, is peculiarly adaptable to be 55 combined with and to form an integral part of the spring member of my clamping device the specific details of which are disclosed and claimed in my beforementioned application; and that due to the fact that 60 the bowed portion 30 of the spring is integral with the resilient extension 36 of the spring, my automatic interlock can be quickly assembled in position on the lower section. It will be further appreciated that in this 65 particular type of device illustrated the

sleeve 16 together with the clamping member thereof acts firmly to hold the two relatively slidable sections in their extreme extended positions and prevents rattle therebetween, and in addition prevents any side 70 play. It will be noted that in the extended position the automatic locking mechanism is disposed between the lower clip 13 on the bottom of the upper section 12, and the sleeve 16 on the upper portion of the lower section 10, thus providing a very rigid interlock. It will be further recognized that due to the shoulder 34 of the spring the lower end of the spring 36 is resiliently 75 pressed against the side of the upper section 12 so that the automatic engagement of the projection 44 in the hole 40 of the spring is assured.

Having thus described my invention what I claim as new and desire to secure by Letters Patent is:—

1. An extension leveling rod comprising a lower section, an upper section, means for slidably holding said sections in assembled relation so that the upper section may be 90 moved to extreme outwardly extended position, and cooperating means carried by said holding means and one of said sections for automatically locking said sections in such extended positions, said co-operating means comprising a pin and a spring latch member adapted to snap over said pin and to interlock therewith when the parts reach extended position.

2. An extension leveling rod comprising 100 a lower section, an upper section, means for slidably holding said sections in assembled relation so that the upper section may be moved to extreme outwardly extended position, and co-operating means comprising a pin carried by one of said sections, and a 105 spring latch member carried by said holding means adapted to snap over said pin and to interlock therewith when the parts reach extended position for locking said sections in such extended position, said means being automatically operable in response to the sliding movement of said sections, the one relatively to the other.

3. An extension leveling rod comprising 115 a lower section and an upper section slidably relative thereto, means carried by said lower section for slidably securing the sections, said means having a leaf spring projecting laterally therefrom in the path of movement of the upper section, said leaf spring having an opening therein and a stud projecting from the lower end of said upper section and adapted to snap into the opening of the leaf spring.

4. An extension leveling rod comprising 120 two relatively slidable sections, one of said sections carrying a sleeve slidable to receive the other section, said sleeve having an adjusting screw carried thereby with the inner 125

end of the adjusting screw arranged substantially to move towards the section sliding through the sleeve, a leaf spring mounted in said sleeve between it and the section sliding through the sleeve and adapted to be engaged by the inner end of the adjustable screw, said spring having an extension formed with an opening adapted to resiliently receive a stub projecting from that face of the section sliding through the sleeve which is adjacent to said extension.

5 5. An extension leveling rod comprising a lower section carrying a sleeve at its upper end, an upper section slideable through said sleeve and carrying a projecting stud on one of its lower faces, an adjusting screw carried by said sleeve with the inner end adjacent said upper section, a leaf spring having a slightly bowed portion positioned between said adjusting screw and said upper section, said leaf spring having a lateral extension overlying the upper edge of the sleeve and an intermediate shoulder underlying the lower edge of the sleeve, said leaf 10 spring having a lower extension provided with an aperture adapted resiliently to receive the projection on the lower end of the upper section.

15 6. An extension leveling rod comprising two sections relatively slideable, a sleeve on one of said sections, a clamp carried by said sleeve and adapted to adjustably lock the other section firmly in extended position, a leaf spring having integral portions adapted to grip said sleeve whereby said leaf spring is held in position by the clamp, said leaf spring having an apertured extension, and a projection on the other section adapted to snap into the aperture of said extension.

20 7. An extension leveling rod comprising two sections, one of said sections carrying a clamp including a clamping screw and a leaf spring adapted to be pressed against the other section by means of said clamping screw, said leaf spring having a portion forming one member of an automatic interlock, and means cooperative with said member for positively locking the two sections in extreme extended position.

25 8. An extension leveling rod comprising a lower section, an upper section, a leaf spring on one of said sections having a bowed portion, the upper end of which is provided with a lateral bent lip, the lower part of the bowed portion being formed to provide a shoulder for gripping said section, the other end of the leaf spring being formed with an outwardly bent portion and provided with an aperture adjacent said outwardly bent portion, and means on the other of said sections for interlocking with said apertured spring section.

30 9. An extension leveling rod comprising a lower section, an upper section slideable with respect to said lower section, and a locking

device including a bowed leaf spring section carried by one of said slideable sections, means for clampingly engaging said bowed section, a second spring section, and means carried by one of said sections for interlocking with said second spring section whereby to retain said leveling rod sections in extended position.

35 10. An extension leveling rod comprising a lower section, an upper section slideable with respect to said lower section, a clamping means carried by one of said sections, a spring section interposed between said clamping means and the other leveling rod section, a second recessed spring section, and a projection carried by one of said leveling rod sections for interlocking with said recessed spring section to maintain said leveling rod sections in extended position.

40 11. An extension leveling rod comprising a lower section, an upper section, clamping means carried by the lower section, a spring section interposed between said clamping means and said upper section, a second locking spring section extending adjacent said upper section, and means on said upper section for interlocking with said second spring section to maintain said leveling rod sections in predetermined extended position.

45 12. An extension leveling rod comprising a lower section, an upper section slideable with respect to said lower section, rod guiding means carried by one of said sections and extending around the other section so as to maintain said sections in proper slideable relation, a clamping means carried by said rod guiding means, a spring carried by said guiding means and extending along one of said rod sections, and means carried by said rod section for lockingly engaging said spring when said rod sections occupy a predetermined extended position.

50 13. An extension leveling rod comprising a lower section, an upper section slideable with respect to said lower section, rod guiding means carried by one of said sections and extending around the other section so as to maintain said sections in proper slideable relation, a clamping means carried by said rod guiding means, a spring interposed between the clamping means and the rod section within the guiding means, a second spring section engaging said guiding means at one extremity and adapted to engage the rod section within said guiding means at its other extremity, and means carried by said rod section for lockingly engaging said second spring section to maintain said rod sections in a predetermined extended position.

55 14. An extension leveling rod comprising two relatively slideable sections, one of said sections carrying a sleeve slideable to receive the other section, said sleeve having an adjusting screw carried thereby with the inner end of the adjusting screw arranged sub-
